(57) **CLAIM**

The ornamental design for a group of buttersticks, as shown and described.

DESCRIPTION

FIG. 1 is a front, top, and left side perspective view of a group of buttersticks;

FIG. 2 is a front elevation view thereof, the back elevation view being identical thereto; and,

FIG. 3 is a top plan view thereof, the bottom plan view, left side elevation, and right side elevation views being identical thereto.

The exterior evenly-spaced broken lines in FIGS. 1-3 illustrate environment that form no part of the claimed design. The interior evenly-spaced broken lines shown in FIGS. 1 and 3 illustrate portions of the group of buttersticks that form no part of the claimed design. The dash-dot-dash broken lines in FIGS. 1 and 3 illustrates the boundary of the claimed design which forms no part thereof. The break lines shown in the middle portion of the group of buttersticks in FIGS. 1 and 3 indicate that the appearance of any portion of the article between the break lines forms no part of the claimed design.

1 Claim, 2 Drawing Sheets
